UNITED STATES PATENT OFFICE.

FRANCIS STICKER, OF NEW YORK, N. Y., ASSIGNOR TO JULIUS C. DRUCK-LIEB AND CHARLES A. DRUCKLIEB, OF SAME PLACE.

STEAM-INJECTOR.

SPECIFICATION forming part of Letters Patent No. 600,455, dated March 8, 1898.

Application filed August 13, 1897. Serial No. 648,165. (Model.)

To all whom it may concern:

Be it known that I, FRANCIS STICKER, of New York, in the county of New York and State of New York, have invented certain new and useful Improvements in Steam-Injectors; and I do hereby declare the following to be a full, clear, and exact description of the invention, such as will enable others skilled in the art to which it appertains to make and use the same.

This invention contemplates certain new and useful improvements in steam-injectors, having reference particularly to the class known to the trade as "locomotive" or "double-jet" injectors.

In two concurrent applications for Letters Patent, filed July 29, 1897, Serial Nos. 646,354 and 646,355, I have pointed out the advantages to be obtained from the employment of a single positively-operated cock for controlling the starting and working, including regulation, of a steam-injector, all valves, movable nozzles, and the like being dispensed with. In said applications I particularly pointed out the advantages of having no pressure to overcome in starting an injector other than that of the atmosphere, and also that not only does the single cock render the use of a check-valve unnecessary to avoid back pressure from the boiler, but all communication between the boiler-outlet and the overflow is entirely avoided.

In the present invention I contemplate the adaptation of a single positively-guided cock to a locomotive-injector, such cock controlling the overflow, the admission of steam, the working of the injector, the regulation thereof, and the passage to the boiler. In this class of injectors as used on locomotives and steam vessels it is normally required that they be capable of sure and effective starting and working almost instantaneous, be entirely independent of any valves in the pipe connections, and be equipped with handle or lever mechanism for controlling a steam-valve for regulating the starting and working of the apparatus. Ordinarily in addition to the valves for controlling the admission of steam automatic valves in connection with or independent of positively-operated

valves have been employed for controlling or affecting the overflow. In addition to the wear on these valves caused by the steam it is well known that the water, being of all sorts and descriptions, according to the different parts of the country, will soon effect a partial if not total destruction of all movable parts, requiring their immediate replacement or the total abandonment of the use of the injector. Most of the water used is more or less filled with dirt, lime, and the like, and this, when the water attains a high velocity, will cause a constant grinding and wear on all the parts with which it contacts. Aside from the deleterious action of the steam and water on all the finely-worked elements of an injector the constant flow of steam and water through narrow valves, holes, or other contracted passages results in great loss from friction, consequently decreasing the power. With all these difficulties in view I have produced an injector of the class mentioned in which they are successfully overcome.

The primary object of my invention is to control the admission of steam to the lifter and forcer by a single cock, which will also control the overflow.

Additional objects are, first, to dispense with all movable parts for controlling the starting, working, and regulation of the apparatus other than a single cock; second, to so locate the tubes of the lifter and forcer that they will have a more suitable position to each other, conforming to the natural flow of water and steam; third, to provide for a direct flow of the steam and water to, through, and from the injector; fourth, combining all overflows in one common chamber, and, fifth, to reduce the number of parts to a minimum and avoid all complications of construction.

The invention will be hereinafter fully set forth, and particularly pointed out in the claims.

In the accompanying drawings, Figure 1 is a view in side elevation. Fig. 2 is a vertical longitudinal sectional view. Fig. 3 is in part a plan view and in part a horizontal sectional view on line 3 3, Fig. 2. Fig. 4 is a horizontal sectional view in part on line 4 4 and in part on line 4' 4', Fig. 2. Fig. 5 is in part an

end view and in part a vertical sectional view on line 5 5, Fig. 2. Fig. 6 is a vertical sectional view in part on line 6 6 and in part on line 6' 6', Fig. 2. Fig. 7 is a vertical sectional view in part on line 7 7 and in part on line 7' 7', Fig. 2. Fig. 8 is a diagrammatical view showing in eight different series the several positions occupied by the different portions of the cock. Figs. 9 and 10 are outside views 10 of the cock. Figs. 11 and 12 are sectional views on lines 11 11 and 12 12, respectively, Figs. 10 and 9.

Referring to the drawings, A designates the casing or casting; a, the steam-inlet; a', the water-inlet; a², the overflow, and a³ the boiler-outlet. The steam-inlet a is located at about the center of the casing, into which it opens and then leads rearward, opening into a vertical conical opening a⁴, which terminates in 20 the overflow a².

B is the lifter, which is located in the upper part of casing A. The position occupied by the lifter—that is, the line of travel induced by the several tubes—is the reverse of that heretofore employed. In other words, the direction of operation of the lifter is away from instead of toward the boiler-outlet. The lifter comprises a steam-tube b, combining-tube b', and delivery-tube b², the two latter 25 tubes being integral. The steam-tube leads from a steam-chamber b³ and opens into a water-chamber b⁴, into which projects the combining-tube. This water-chamber b⁴ communicates with the water-inlet a' by a cored passage-way b⁵, one on each side of the casing. The delivery-tube b² opens into a discharge-chamber b⁶ at what is normally the receiving 30 end of the apparatus. Steam is admitted to the steam-chamber b³ through side channels b⁷, running parallel with the inner horizontal branch of steam-inlet a. A horizontal partition b⁸, extended longitudinally within the casing, separates the lifter from direct communication with the lower portion of the 35 casing.

D is the forcer, the line or direction of operation of which is the reverse of that of the lifter. In other words, its feeding is directly toward the boiler-outlet. Of the forcer, d is the 40 steam-tube, d' the combining-tube, and d² the delivery-tube. The steam-tube extends at its receiving end into a steam-chamber d³ and at its other end into a water-chamber d⁴, in which is also located the combining-tube. This 45 water-chamber communicates with the discharge-chamber b⁶ of the lifter by cored passages d⁵ in each side of the casing. Hence water discharged by the lifter will flow downward from chamber b⁶ into the water-chamber d⁴ of the forcer. This water-chamber d⁴ is formed with a lower elongation d⁶, terminating in an auxiliary overflow-opening, said elongation forming the channel for the overflow from the lifter as well as that occurring at the mouth 55 of the forcer combining-tube. The delivery-tube d² is mounted in a partition d', forming a discharge-chamber d⁸ for the forcer. The

primary overflow occurring at the end of this delivery-tube will pass out through the open end of this chamber d⁸ into the opening a⁴. 70

E is the forcer steam-channel, running longitudinally of the apparatus, being formed by the horizontal partition b⁸ and a lower corresponding partition e. This channel E extends from the vertical opening a⁴ to and 75 opens at its other end into the steam-chamber d⁸.

In practice steam is first admitted in a small quantity to the lifter, and after passing through the latter and down to the water-chamber of the forcer, and thence to the atmosphere, water is lifted. While this is occurring no steam is admitted to the forcer, but instantly upon establishing the column a full head of steam is admitted to the forcer 80 and also to the lifter, all overflows being positively closed. The capacity of the machine may be regulated by controlling the steam-supply to the lifter. I will now describe how 85 all these functions are controlled by a single 90 positively-operated medium.

F is a cock tapered throughout its length and held snug in conical opening a⁴ by a stuffing-box f. A rod f' extends upwardly from this cock and is fitted with a handle f². This 95 cock is centrally divided into upper-and lower chambers f³ f⁴ by a horizontal partition f⁵, the upper being the steam-chamber and the lower the overflow-chamber. Extending transversely through the latter is the delivery-port f⁶, which is formed in a web depending from partition f⁵. This port f⁶ when in line 100 with the delivery-tube of the forcer opens up communication between the latter and the outlet to the boiler. In one side of the cock 105 is an overflow-port in the form of a deep groove or cut-away f⁷, which opens into the chamber f⁴ and is designed to receive the overflow from the discharge-chamber and delivery-tube of the forcer. Beneath this port 110 is a second port f⁸, which allows the overflow from the channel d⁶ to pass into the cock and thence to the atmosphere. Thus it will be 115 seen that all overflow reaches the atmosphere through the ports in the lower chamber of the cock.

In the upper part of the cock are formed two oblong ports g g', one above the other, the former being designed to register with the steam-inlet a and the latter with the steam-channels b⁷ and E. The outlet-port g' is made 120 slightly larger than the receiving-port. I have shown the cock formed with two sets of these steam inlet and outlet ports, thereby enabling the apparatus to be operated by 125 turning the cock either to the right or to the left. Until the column of steam and water is established the boiler-outlet is tightly closed by the cock F; but even when the delivery-port first approaches coincidence with the 130 forcer and boiler-outlet no communication is established between the latter and the overflow. Hence there can be no deleterious results from boiler back pressure.

In operation when the cock F occupies the first position (indicated by Fig. 8) steam admitted to the inlet a is prevented from entering the injector by means of said cock; but when partly turned (see third position) steam will pass into the steam-chamber of said cock and out through port g' into one of the channels b⁷, supplying steam to the lifter, the channel E being closed. As the steam passes through the lifter-tubes and down through water-chamber d⁴ and channel d⁶ it will enter the overflow-chamber of cock F through port f⁸, and upon reaching the atmosphere will entrain the air and steam from the injector, creating a vacuum in the water-chamber of the lifter, so that water will be drawn to the lifter. No steam being yet admitted to the forcer, there is no back pressure to retard the lifting of water. The water being taken up by the steam-jet will be discharged into chamber b⁶ and passing downward to the forcer will escape to the atmosphere through channel d⁶ and chamber d⁸, with which register the lower and upper overflow-ports, respectively, of the cock. The converging tubes and the overflows concentrate the column of steam and water and increase its velocity in the combining-tube of the lifter, thereby rendering further overflow for the lifter unnecessary. Thereupon by giving the cock a still further turn (see fifth position, Fig. 8) the lower port g' will be brought into line with steam-channel E, allowing steam to enter the forcer, and at the same time the cock will partly close the overflow from channel d⁶, but any back pressure can still find outlet through the overflow-ports of the cock to such an extent as not to interfere with the water and steam concentrating and entering the combining and delivery tubes of the forcer. A further turning of the cock closes entirely the lower overflow, (see sixth position, Fig. 8,) and the full head of steam being admitted to channel E and the column having attained its full velocity the upper overflow is closed through port f⁷, and the delivery-port f⁶ is gradually brought into line with the delivery-tube of the forcer and the boiler-outlet. The forcer being now fully supplied with steam and all overflow cut off, the cock is further turned, (see seventh position, Fig. 8,) opening up communication with the second steam-channel b⁷, leading to the lifter, thereby increasing the steam-supply to the lifter and making the now established column powerful enough to enter the boiler through the now fully-opened delivery-port in the cock. A still further turning of the cock (see eighth position, Fig. 8) will close one of the steam-channels leading to the lifter, thereby reducing the head of steam to the lifter, and consequently reducing the lifting power and hence capacity of the apparatus.

From what has been said the advantages of my invention will be apparent. In the first place it will be observed that the lifter per-

forms its duty entirely independent of and free from any interruption by the forcer. The supply of steam to the lifter is independent of that to the forcer, although controlled by a common agency—to wit, the single cock. This cock not only controls the steam-supply to both the lifter and forcer, but also regulates the capacity of the machine. By arranging the cock in the manner stated I am enabled to start, work, and regulate the injector by a single device. As the cock is the only movable part employed in the construction of the injector, the latter is not liable to readily get out of order, nor is it possessed of any parts liable to suffer from the action of steam and water.

I claim as my invention—

1. A lifting and forcing injector having the lifter and forcer arranged in parallelism, one above the other, the receiving and discharging ends of the tubes of one being faced in opposite directions to the receiving and discharging ends of the tubes of the other, substantially as set forth.

2. A lifting and forcing injector having the lifter and forcer arranged in parallelism, one above the other, the receiving and discharging ends of the lifter being faced in opposite directions to the receiving and discharging ends of the forcer, substantially as set forth.

3. A lifting and forcing injector having the lifter and forcer arranged in parallelism, said lifter being positioned above the forcer, the receiving and discharging ends of the lifter being faced in opposite directions to the receiving and discharging ends of the forcer, substantially as set forth.

4. A lifting and forcing injector having the lifter and forcer arranged in parallelism, said lifter being positioned above the forcer, separate steam-channels for said lifter and forcer, and a single cock having a steam-chamber and a port for coinciding with said steam-channels, substantially as set forth.

5. A lifting and forcing injector, the casing of which is provided with a steam-inlet having an inner branch, a lifter arranged in the upper portion of said casing, and a forcer below said lifter, a cock fitted in said casing intercepting said branch and having a chamber into which said steam-inlet opens, and a port in said cock for controlling separate outlets of steam to said lifter and forcer, substantially as set forth.

6. In a lifting and forcing injector having steam and water inlets, overflow and boiler outlets, a single cock extending through the injector having a series of ports for controlling the inlet of steam and also controlling the overflow and boiler outlets, as set forth.

7. A lifting and forcing injector having an upper steam-inlet, a lower overflow, a boiler-outlet, and separate channels leading, respectively, to the lifter and forcer, and a chambered cock extending through the injector having separate ports for establishing communication between said steam-inlet and the

said channels, and controlling the overflow and boiler-outlet, substantially as set forth.

8. A lifting and forcing injector having an upper steam-inlet, a lower overflow, a boiler-outlet, separate channels leading to the lifter and a third channel leading to the forcer, and a chambered cock extending through the injector having a port for establishing communication between said steam-inlet and one or both of said separate channels and also said third channel, and having ports for controlling the overflow and boiler-outlet, substantially as set forth.

9. A lifting and forcing injector having separate steam-channels for the lifter and forcer, and two overflows, and a single cock for controlling steam to said channels and also controlling both of said overflows, substantially as set forth.

10. A lifting and forcing injector having an upper steam-inlet, separate channels leading, respectively, to the lifter and forcer, and also having primary and auxiliary overflows, and a chambered cock extending through the injector having separate ports for establishing communication between said steam-inlet and said channels, and lower ports for controlling the said overflows, substantially as set forth.

11. A lifting and forcing injector having an upper steam-inlet, separate channels leading, respectively, to the lifter and forcer, and also having primary and auxiliary overflows, and a cock having upper and lower chambers, said upper chamber having ports for establishing communication between said steam-inlet and said channels, and said lower chamber having ports for controlling said primary and auxiliary overflows, substantially as set forth.

12. A lifting and forcing injector having a steam-inlet and a boiler-outlet, the latter being in line with the forcer, and a chambered cock having ports for establishing communication between said steam-inlet and the lifter and forcer, and also having a port for opening up communication between said forcer and boiler-outlet, substantially as set forth.

13. A lifting and forcing injector having a steam-inlet and a boiler-outlet, the latter being in line with the forcer, and a chambered cock having separate ports for establishing communication between said steam-inlet and, first, the lifter and then the forcer, and a third port for opening up communication between said forcer and boiler-outlet, substantially as set forth.

14. A lifting and forcing injector having a steam-inlet and a boiler-outlet, the latter being in line with the forcer, and also having primary and auxiliary overflows, and a chambered cock having ports for establishing communication between said steam-inlet and, first, the lifter and then the forcer, and also having ports for closing, first, said auxiliary and then said primary overflows, and a transverse port for opening up communication be-

tween said forcer and boiler-outlet, substantially as set forth.

15. In a lifting and forcing injector having a steam-inlet, the lifter having two steam-channels paralleling said steam-inlet, and a third channel leading to the forcer, and a cock having a chamber and separate ports, one of said ports controlling the passage of steam from said inlet to said chamber and the other port controlling the passage of steam to the channels leading to the lifter and forcer, substantially as set forth.

16. A lifting and forcing injector having its casing provided with an intermediately-arranged steam-inlet, and a vertical opening intercepting said inlet, channels leading from said opening to the lifter and a third channel leading to the forcer, and a cock fitted in said opening having a chamber and ports for controlling the passage of steam from said inlet to said channels, substantially as set forth.

17. A lifting and forcing injector having its casing formed with an upper steam-inlet, a vertical opening, steam-channels leading from said opening to the lifter, and a separate steam-channel leading to the forcer, said channels of the lifter being on opposite sides of said channel of the forcer, and a cock fitted in said opening having a steam-chamber and ports, one designed to register with said steam-inlet, and the other with said steam-channel of the forcer and one or both of said channels of the lifter, substantially as set forth.

18. The injector herein described comprising the casing having a centrally-disposed steam-inlet and a vertical opening intercepting said steam-inlet, the lifter having a steam-chamber provided with two channels, the forcer, a steam-channel arranged longitudinally within said casing and extending from said opening to said forcer, lower overflows, and a single cock having an upper steam-chamber and a lower overflow-chamber, said steam-chamber having ports for controlling the passage of steam to said channels, substantially as set forth.

19. The injector herein described having the overflow-openings for the lifter and forcer in the lower portion of its casing, and an upper steam-inlet, and a cock having an upper steam-chamber and a lower overflow-chamber, said cock having in one side a cut-away opening and a lower opening forming overflow-ports, and a transverse port for opening up communication between the forcer and the boiler-outlet, substantially as set forth.

20. In an injector having its casing provided with a vertical opening, an upper steam-inlet and steam-channels leading into and from said opening, and lower overflows, a cock fitted in said opening having a central partition forming upper and lower chambers, said upper chamber having upper and lower ports for forming communication between said steam-inlet and steam-channels, and said lower chamber having a lower port and an

upper cut-away port, and a delivery-port, substantially as set forth.

21. The herein-described injector having its casing formed with an upper intermediate steam-inlet, a vertical opening between said steam-inlet and the boiler-outlet, a cock fitted in said opening normally closing said boiler-outlet and having an upper steam-chamber provided with upper and lower ports, a lower overflow-chamber having ports therein, a delivery-port extending transversely through said lower chamber, the lifter having a steam-chamber adjoining said steam-inlet, channels leading from said vertical opening to said steam-chamber, the forcer, a third channel

leading from said opening to said forcer, passage-ways between the water-inlet and said lifter and between the discharge-chamber of the lifter and the water-chamber of the forcer, and an overflow-channel leading from said water-chamber of the forcer to said vertical opening, substantially as set forth. 20

In testimony whereof I have signed this specification in the presence of two subscribing witnesses.

FRANCIS STICKER.
